BRIDGE SCORING DEVICE

Filed June 6, 1927

2 Sheets-Sheet 2

Inventor:

Volmer Leopold Undset Gyth

By *June Daniels*
Attorney.

UNITED STATES PATENT OFFICE.

VOLMER LEOPOLD UNDSET GYTH, OF COPENHAGEN, DENMARK.

BRIDGE-SCORING DEVICE.

Application filed June 6, 1927, Serial No. 196,967, and in Denmark May 18, 1927.

Score-keeping in the game of bridge is effected by recording, on a sheet of paper, above and below a horizontal line on the same as the case may be, the points scored by the 5 two or three playing parties, for each party in a separate column, whereafter the account is made up later on by addition of the thus recorded point numerals in accordance with the rules of the game.

10 This score-keeping requires much care in order to prevent disagreements between the players, and the present invention has for its object to facilitate the score-keeping. According to the invention the account is kept 15 solely by adjustment of slides or the like on a special support, base, or board whereby any recording of points etc. on paper will be rendered superfluous, the players being at the same time enabled to ascertain at any moment, 20 simply by direct inspection of the board, the precise state of the game.

One construction of such apparatus in board-shape is illustrated on the drawing, where

25 Fig. 1 shows the scoring board in zero-position, i. e. at the commencement of the game,

Fig. 2 is a longitudinal section along the line II-II of Fig. 1.

30 Fig. 3 is a cross-section along the line III-III of Fig. 1.

35 Figs. 4 and 5, show diagrammatically, the adjustment of the scoring board at a certain moment during the first played game and after the final closure of the same, respectively, i. e. at the commencement of the next game.

40 In order to avoid crowding the drawings only a few of the numerals of the scales have been indicated, and these numerals are placed outside of the figure concerned.

45 In the construction shown, the scoring board is rectangular and is provided, on its left-hand side, with seven grooves or tracks parallel to the long side of the board (the two inner ones and the two outer ones covering one another in pairs) and slides inserted

50 therein and with corresponding scale divisions for registration of the scores of one of the playing parties, and on the right-hand side of the board an exactly similar arrangement for registering the scores of the other party. The two sets of slides, one for each party, are each marked at the top end of the board, viz "We" corresponding to the accountant with his partner, and "They" corre-

sponding to their adversaries. In the following only one of the two similar sets of slides will be described.

A direct registration of scored points "above the line" i. e. above a transverse line *a* drawn on the surface of the board, which points according to the rules of the game are often a multiple of 50, is effected by means of the central slide *b* which in its zero-position is entirely covered below the surface of the board in such a manner, consequently, that when the slide occupies its zero-position the upper half *c* of the track or groove of the slide *b* will be entirely open. The bottom of the said groove supports a numeral scale 70 divided into 100's up to 1000 with intermediate division lines for every 50. This scale, however, may also be drawn on the surface of the slide *b* or on the face of the board along the edge of the groove. In any case the initial point of the scale must be at the transverse line *a* when the slide occupies its zero-position.

55 Direct registration of scores "below the line," i. e. below the transverse line *a* is effected 80 by means of two other slides, viz a slide *d* to the left of the slide *b* (see Fig. 1) and a slide *e* to the right of the slide *b*, the said two slides *d* and *e* being placed at one and the same depth below the surface of the board (Fig. 85 2). The scale corresponding to the slide *d* is placed on the surface of the board with its zero-point at the transverse line *a*, and extends downward from the said line along the edge of the groove *f* of the slide, and is divided into 10's up to 100. In corresponding manner the scale of the slide *e* extends downward below the transverse line along the groove *g* of the slide *e*, and is divided into units up to 10. If the scale of the slide *d* were 90 divided into units up to 100, the slide *e* and the corresponding groove *g* might be dispensed with. The scales may also be disposed at the bottom of the slide grooves or on the slides *propter*.

100 At its zero-position the slide *d* is covered entirely by a slide *h* disposed at a higher level, and the slide *e* is similarly covered by a correspondingly disposed slide *i*. These two slides *h* and *i* are of the same length as the slides *d* and *e*, and their scales are disposed on the surface of the board alongside the grooves concerned and are divided in the same manner as the scales for the slides *d* and *e*, but their zero-points are disposed above 110

the transverse line *a*, in such a manner that the scales at the said transverse line show 100 and 10, respectively.

Above the transverse line *a* there is finally provided a small slide *j*, and below the transverse line a small slide *k*. The first mentioned slide may be adjusted so as to show through a small window, the numerals 0, 1, 2, 3 etc. which numerals, in combination with three zeros printed on the surface of the board to the right of the window, indicate the entire number of full thousands gradually scored by adjustments of the slide *b*. The slide *j*, when in its zero-position, shows the figure 0 in the window and is in fact adjusted so as to show 1000 when this figure has been reached on the scale of the slide *b*, and the slide *b* is simultaneously pushed back into its zero-position, in such a manner that it will again be ready to sum up the scored 100's, 50's etc. The small lower slide *k* shows, through a small window, the number of games won, the said slide being adjusted, after the finish of each game, to show the number of the same.

The scoring board, in the construction illustrated, is supposed to be made from five celluloid sheets placed on top of each other and formed with the required number of slots serving as tracks for the slides and with the required observation windows, and the sheets are then joined together so as to form a unit. It will easily be understood that by such construction of the board the several slides which are likewise supposed to be made from celluloid, will move perfectly independently of each other in their individual grooves or tracks. Their adjustment is effected by means of knobs *l* attached to the slides and projecting through the slots in the board so far above the surface of the latter that they may easily be gripped by two fingers. In order to facilitate the proper adjustment of the slides and to increase reading facility, the two sets of slides *b*, *d* and *e* ought to be differently coloured, for instance red for "They," blue for "We," when the board is of neutral colour, or vice versa. The slides *h* and *i*, on the contrary ought to be of the same colour as the board, but their grooves above the line *a* should be coloured similarly to the other slides belonging to the same set.

At top of the board there is provided a ruled space for notation of the results of the individual rubbers, and at bottom a table of trick values is printed.

During the play the scoring board is used for instance in the following manner, after all the slides have been placed in their zero-positions. If during the first deal "They" gain 150 points "above the line," the slide *b* of the "They" set is adjusted at 150; then, if during the second deal "We" gain 300 points above the line, the slide *b* of the "We" set has to be placed at 300. If now during

the third deal "They" win "three hearts," i. e. 24 points "below the line," the slide *d* is set on 20 and the slide *e* on 4. The state of the game thus assumed by way of example is shown in Fig. 4. If then during the fourth deal "They" make 50 points above the line, the slide *b* of the "They" set must be changed from its position (150 points) to the position 200, and if "We" in the fifth deal win 100 points "above the line," the slide *b* of the system "We" has to be moved from its position (300 points) into the position 400. If then during the sixth deal "We" attain "4 spades," i. e. 36 points "below the line," whereby the first game according to the rules of play is finished, the slides *d* and *e* of the "We" set are moved to 30 and 6, respectively. As a new game has now to be begun, the rules require that the score (24 points) of "They" "below the line" be cancelled there but be included in the final result, and the slides *h* and *i* are, therefore, pushed down so as to cover entirely the slides *d* and *e*, whereby the scores below the line become transferred directly "above the line," the said scores appearing above the top ends of the slides *h* and *i*. The thus produced state of the game is illustrated in Fig. 5.

When the next new notation "below the line" for "They" is marked by pushing downward the slides *d* and *e*, the initial points of these notations will be the lower ends of the just adjusted slides *h* and *i* etc. When the score is to be finally settled at the end of the rubber, the slides *h* and *i* are pushed down so as to cover completely the slides *d* and *e*, and the result may then be read above the horizontal line *a* by addition of the readings on the two sets of slides *j*, *b*, *h* and *i* separately, the said readings giving immediately the figures representing 1000's, 100's, 50's, 10's and units.

Having now particularly described and ascertained the nature of my said invention and in what manner the same is to be performed, I declare that what I claim is:—

1. A scoring device for bridge, comprising a support provided with a transverse division line and with a plurality of longitudinal tracks intersecting such line, each track portion both above and below the line having a graduated scale associated with it; a slide mounted in one track for directly registering on the corresponding scale the points scored above the line; a set of slides mounted in the remaining tracks for directly registering on the corresponding scales the points scored below the line; and a set of slides overlying the first set of slides and of equal length therewith for transferring the points scored below the line onto the corresponding scales above the line.

2. A bridge-scoring device, according to claim 1, in which the track receiving the slide that registers directly the points scored above

the line terminates at its lower end at said line; and in which the remaining tracks are bisected by the line.

3. A bridge-scoring device, comprising a support provided with a transverse division line; a track extending above such line from its lower end; a slide movable therein for registering on a graduated honor-point scale the points scored above the line; a pair of tracks intersecting said line and having portions of equal length extending above and below the same, such portions having reversely-graduated trick-point scales associated with them; a pair of slides movable in said pair of tracks for registering directly on the lower

trick-point scales the points scored below the line; and a set of slides directly overlying the first pair of slides for subsequently transferring the points scored below the line into the upper trick-point scales.

20

4. A bridge-scoring device, according to claim 3, in which the transfer slides are of the same length as the trick-point slides so as to cover them completely when both are in zero position, and are movable in the same direction as said trick-point slides.

25

In testimony whereof he affixes his signature.

VOLMER LEOPOLD UNDSET GYTH.
